UNITED STATES PATENT OFFICE

LOUIS PFEFFER, OF MAYSVILLE, KENTUCKY, ASSIGNOR TO PFEFFER PRESS COMPANY,
INCORPORATED, OF MAYSVILLE, KENTUCKY

TOBACCO PRESS

Application filed February 10, 1926. Serial No. 87,279.

This invention relates to a tobacco press and is primarily designed to be used by the farmer or producer of leaf tobacco in order to place the "hands" of tobacco in proper 5 form in preparing it for market.

It is also an object of this invention to prevent the tobacco while in the form of "hands" and in "case" from drying and thereby becoming harsh and breakable and out of "case" 10 with a consequent waste of tobacco.

A further object of my invention is to enable the producer to load his product and take it to market at any time regardless of the weather conditions.

15 The method heretofore used by producers has been to pile the tobacco while in "hands" in bulks and then to lay boards or other weights upon the bulks so as to cause the tobacco to settle or press after a fashion.

20 This is deleterious to the tobacco due to the crumpling caused and also to the haphazard piling of the "hands" and the unequal pressure exerted upon individual "hands".

25 My invention contemplates the remedying of these defects by taking the tobacco as soon as stripped and tied into "hands" and supporting "hands" in a vertical position in the press while the tobacco is put under pressure.

30 An additional object of my invention is to provide a device which will accommodate an entire day's work of a man stripping tobacco so that the tobacco will remain under pressure in the press for some hours before it is taken out and put in bulk.

35 A further object is to provide a device which is capable of handling a plurality of sticks of tobacco, each stick carrying from fifteen to twenty "hands" so that the worker 40 need merely add each additional stick as he finishes it to those already in the press.

45 With these and other objects in view as will appear as the description proceeds, the invention consists in the construction, arrangement and combination of the various parts of my device whereby the objects contemplated are attained, as hereinafter more fully set forth, pointed out in my claims and illustrated in the accompanying drawing, in 50 which:

Figure 1 is a side elevation of my device.

Figure 2 is a front elevation.

Figure 3 is a vertical cross sectional view taken on line 3—3 of Figure 2 looking in the direction of the arrows. 55

Figure 4 is a plan view.

In the drawings similar reference characters indicate like elements in the various figures. 60

Referring to the drawings, 10 and 11 indicate two spaced base members upon which are supported in spaced relation the four standards 12, 13, 14 and 15 which support the two sides 16 and 17 and the back 18. These parts are shown as made of wood although it is understood that any other material may be used. The sides and back are shown spaced from the base elements 10 and 11 although if desired they may be extended to them. The front of my device is left open. 65 70

Extending parallel with the sides and spaced above them are bars 19 and 20 having notches 21 upon the upper side thereof. The bars 19 and 20 are supported at the back portion of my device by extensions of the 75 standards 14 and 15 and are secured thereto by the bolts and nuts 22.

The forward parts of the bars 19 and 20 are supported by U-shaped members 23 and 24 with the openings thereof extending towards the centre. The members 23 and 24 are secured to the standards 12 and 13 respectively by the bolts and nuts 25. 80

A swinging door 26 is pivoted from a bar 27 which rests in a pair of aligned notches 85 21 by means of metal straps 28 and 29 secured to cleats 30 and 31 upon the back of the door 26 by bolts and nuts 32.

The straps 28 and 29 below the door are bent toward one another and terminate in 90 forwardly extending ears 33 and 34 respectively to which a handle 35 is pivoted.

Above the pivot point of the handle a link 36 is pivoted to the handle and below the handle pivot a smaller link 37 is pivoted upon 95 the handle. Extending longitudinally of my device and joining the central portions of the bars 10 and 11 is a bar 38 having ratchet teeth 39 with which the links 36 and 37 cooperate so as to form with the handle 35 a 100

jack mechanism for urging the door 26 towards the back 18 in order to press the "hands" of tobacco between the door and the back.

In Figure 3 a "hand" of tobacco 40 is shown supported on the stick 41 which rests upon the upper edges of the sides 16 and 17 below the bars 19 and 20. In Figure 4 four sticks of tobacco are shown in position carrying a plurality of "hands".

For raising the door in order to allow of the insertion of a stick of tobacco pulleys 42 and 43 and the weight 44 are provided. The pulley 42 is mounted on the standard 45 and the pulley 43 may be supported upon any external support as the side of a barn etc. In the drawings it is shown mounted on the standard 46 at the back of the device. The weight 44 is secured to a cable or rope 47 which passes over the pulley 43, then over the pulley 42 and is then fastened in any desired manner to the lower portion of the door as shown at 48 in Figure 2.

In Figure 2 it will be noted that the U-shaped members 23 and 24 allow the sticks to be inserted upon the top edges of the sides 16 and 17 when the door is raised by the weight.

The standards 12, 13, 14 and 15 are secured to the base members 10 and 11 by angle irons 49 and the standards are braced by the braces 50.

The operation of my device is as follows: The worker having stripped the "hands" of tobacco places them upon a stick 41. The door 26 is then raised so as to leave the space between the bars 19 and 20 and the tops of the sides clear. He then slides the stick against the back 18 and shakes it so as to straighten out the leaves of tobacco. The door is now lowered against the weight and the links 36 and 37 will engage the ratchet teeth 39 of the bar 38. By moving the handle 35 back and forth any desired pressure may be exerted against the "hands" of tobacco. When the next stick is ready the door is raised and the new stick is placed against that already in the machine and the operation repeated. As additional sticks are inserted the bar 27 carrying the door is moved step by step in the notches 21 towards the front of the machine.

At the completion of a day's work, all the sticks are removed and the tobacco placed in bulk and due to the straightened condition of the leaves and the pressure the tobacco is prevented from getting out of "case" and in addition it can be carted to market whenever desired since it is never permitted to get out of "case". Furthermore due to this method and machine the quality of the tobacco is greatly improved with a consequent advantage to the producer.

Some changes may be made in the construction and arrangement of the invention above set forth without departing from the real pur-

pose and spirit thereof and it is my intention to cover by the following claims any modified forms of structure or use of mechanical equivalents which may be reasonably included within their scope.

I claim:—

1. In a device of the class described, spaced side walls, a back connecting said walls, bars extending parallel to said walls, a pressing element supported from said bars, a notched bar extending below said walls and a jacking mechanism carried by said element co-operating with said notched bar.

2. In a device of the class described, spaced side walls, a back connecting said walls, notched bars above said walls, a pressing element supported from said bars, a bar extending below said walls and a jacking mechanism carried by said pressing element co-operating with said lower bar.

LOUIS PFEFFER.
